(57) **CLAIM**

The ornamental design for a lamp, as shown and described.

DESCRIPTION

1. Lamp

1.1 : Perspective

1.2 : Front

1.3 : Rear view

1.4 : Bottom

1.5 : Top

1.6 : Right side view

1.7 : Left side view

Lamp in the shape of a squirrel, preferably for outdoor use; the lamp is provided with two light sources, respectively located inside the base and inside the nut; the nut is detachable to be used independently.
